UNITED STATES PATENT OFFICE.

ALEXANDER BEVAN, OF PROVIDENCE, RHODE ISLAND, ASSIGNOR TO THE RECORD ELECTRIC RAILWAY SIGNAL COMPANY, OF PROVIDENCE, RHODE ISLAND, A CORPORATION OF RHODE ISLAND.

CIRCUIT-CLOSER FOR TROLLEY-SIGNALS.

No. 836,062.

Specification of Letters Patent.

Patented Nov. 13, 1906.

Application filed February 6, 1906. Serial No. 299,771.

To all whom it may concern:

Be it known that I, ALEXANDER BEVAN, a citizen of the United States, residing at the city of Providence, in the county of Providence and State of Rhode Island, have invented certain new and useful Improvements in Circuit-Closers for Trolley-Signals, of which the following is a specification, reference being had therein to the accompanying drawings.

The present invention relates to an electric switch, and is embodied in a switch for railway signaling and analogous purposes in which the contacts are operated by the movement of a traveling object, such as a suitable projection or engaging portion carried by a car or vehicle.

As herein shown, the switch is arranged to be operated by the trolley of an electric car, and is especially adapted for use with a block-signaling system for electric railways in which certain signals are set when the car enters a block and put out when the car leaves the same.

It is essential that a switch of this kind should be positive in its operation and that a good contact should be made for a sufficient length of time whether the car which operates the switch is traveling at a high speed or not. The contact made by the trolley upon the actuating-lever is ordinarily very short, even if the car is running at a moderate speed, and when the car proceeds at a high speed the contact on said lever is so short as to be entirely ineffective. Means therefore have been provided for prolonging the electrical contact period to a suitable length of time to properly operate the signals that may be located at some distant point.

A further object of the invention is to so construct the device that a single actuating-lever may be employed to operate each of a pair of contact-arms, so that by moving said lever in one direction one of said contacts will be closed and when moving in the opposite direction the other contact will be closed.

It is also desirable to arrange the switch with two sets of independent mechanism, each of which are operated by the single actuating-lever, and I have found it most essential in practice that positive stopping means should be employed to engage and prevent said actuating-lever from swinging backward, engaging and operating the mechan-

ism on the opposite side, causing what is known as a "back contact." As is well known, when this back contacting occurs the signals are again acted upon, completely disarranging the whole system, which then becomes unreliable.

To attain these objects, the switch embodying the present invention is shown as provided with two sets of contact-makers having a common actuating-lever independent of said contact-makers, but adapted by its movement in one direction to operate one contact-maker and by its movement in the other direction to operate the other contact-maker, and said actuating-lever is prevented by a positive stopping mechanism from moving back by its own momentum past its normal or intermediate position.

Another feature of this invention is the arrangement of the retarding mechanism by which I am enabled to completely control the period of contact entirely independent of the throw of the actuating-lever. It is found in practice that when a car is traveling at a high rate of speed the actuating-lever and its engaging mechanism is thrown farther than when the car is passing more slowly. Then, again, all trolley-wheel grooves are not of the same depth, some after having been worn have deeper projecting flanges. This also has a tendency to throw the actuating-lever a greater or less distance. To compensate for this uneven stroke in the mechanism, I have arranged a vent-hole in the retarding-cylinder, so that the attending mechanism will return quickly to a given point. Then it will move slowly until the contacting finger is about to break its connection, when the mechanism will drop quickly, causing said connection to break quickly. This feature of having the mechanism start back quickly to a given point before it is retarded is a new feature and nicely controls the exact period of contact.

The invention consists of other novel features and parts and combinations of the same, as will be fully described hereinafter and then pointed out in the appended claims.

A practical embodiment of the invention is represented in the accompanying drawings, forming a part of this specification, in which similar characters of reference indicate corresponding parts in all the views.

In the drawings, Figure 1 is a side elevation of the contact-box and mechanism, partly in section, showing two sets of independent mechanism, one set in the up or closed position and one set in the down or open position. Fig. 2 is an end view of the same. Fig. 3 is a central sectional end view of the device.

Referring to the drawings, at 1 is the base-plate of the device, on which the mechanism is mounted. This base itself is preferably supported from the trolley-wire in the usual way, (not shown,) or it may be supported by any other means adjacent to said wire. On this base is mounted two supporting side frames 2 2. At 3 is the actuating-lever pivoted to the frame at 4 to swing freely in either direction. The lower end of this lever is preferably forked, as shown in Figs. 2 and 3, to straddle the trolley-wire 5 when in its down position. Pivoted at 6 in the upper end of this lever is the contact-roll 7, that is held to turn freely when it engages either of the knee-levers 8 8 on either side of the roll 7. At the upper end of this actuating-lever are fixed the two lugs or projections 7^a, one on either side of the roll 7.

In constructing my device I have made two sets of independent mechanism and located the same one at each side of the center of the box, each set being an exact duplication of the other. At 9 is a piston held to oscillate slightly by being pivoted to the frame at 10. This piston is provided with an inlet air-passage 11 through it, communicating with its upper end, the opening in which passage is controlled by the ball-valve 12, set into the enlarged hole 13. At 14 is another air-passage extending downward from the upper face of the piston, part way through the piston, and then out through its side at 15. Sliding vertically over this piston is the cylinder 16, the bottom of which is open and the top covered with the cap 17. Through the side of this cylinder is formed the vent-hole 18, the vertical position of which hole determines the distance of the first quick drop of the cylinder after being released by the operating-lever, and the period of time the cylinder is traveling from the top face of the piston to the hole 15 determines the protracted period of contact. Projecting upward from the cap 17 is the ear 19, to which is pivoted at 20 the longitudinal arm 8^a of the knee-lever 8. This lever is pivoted in turn to the frame at 21, and its depending arm extends down into position to be engaged by the roller 7 in the upper end of the swinging actuating-lever 3. Pivoted on this downwardly-extending arm at 20 is the roll 31, that extends out laterally therefrom to engage the stop-lever, hereinafter described. On the under side of the arm 8^a is secured the hooked finger 25.

Pivoted at 22, directly beneath the longi-

tudinal arm 8^a of the knee-lever, is the contact-lever 23, the lower end of which lever is adapted to swing into and out of engagement with the contact-fingers 24. This lever is also provided at its upper end with an arm 24^a, extending outward from the center approximately at right angles thereto. The end of this arm is adapted to be engaged and drawn upward by the said hooked member 25, thereby positively throwing the lower end of said lever into contact with the contact-fingers 24. These contact-fingers 24 are mounted on the insulated block 32, and to them is connected the conductor-wire 33 by means of the binding-post 34.

Pivoted at 26 to the frame is the stop-lever 27, the outer end of which is turned down at 28 in the form of a hook and adapted to engage the lug 7^a on the upper end of the actuating-lever 3. This hooked end 28 is normally held up out of engagement with said actuating-lever by the tension of spring 29, said lever being forced down into position to engage and stop the backward swing of the actuating-lever by the engagement of the roll 31 on the inclined upper edge of said lever 27 as the said knee-lever is forced outward from its rest position.

The trolley-wire in this device constitutes a part of the circuit controlled by the switch or contacts, being electrically connected with said wire in any desired manner, usually through the metallic framework of the device. (Not shown.) The arrangement of the circuits is, however, immaterial so far as relates to the present invention, which resides in the construction and mode of operation of the switch mechanism.

The operation of the device may be further described as follows: The two sets of mechanism shown are both operated by the swinging depending actuating-tongue 3. In Fig. 1 of the drawings this tongue is shown as having been operated by a car passing to the right, and in traveling to this position it has operated the left-hand mechanism. The group of mechanism at the right of the central line is shown in its down or normal position, illustrating its contact-arm as being out of connection with its contact-fingers. As the actuating-lever is moved by the passing trolley, the contact-roll engages the downwardly-extending arm 8 of the knee-lever and through it raises the retarding-cylinder 16. At the same time the hooked member 25, that engages the end of the arm 24^a, raises this arm and positively throws the contact-lever 23 into connection with the contact-fingers 24. After this connection has been made the arm 8^a of the knee-lever continues upward, leaving the arm 24^a in said contact position. The same stroke of the depending knee-lever also causes the roll 31, pivoted thereto, to engage the inclined surface 35 of the stop-lever 27, causing said

stop-lever to be forced downward into position to engage the lug 7^a on the upper end of the actuating-lever and positively prevent said lever from swinging backward beyond its central position when the same is released after the trolley has passed beneath it. Were it not for this stop this lever after being struck by the rapidly-moving trolley-wheel would rebound and have a tendency to swing over and engage the mechanism on the opposite side, causing the same to make another or back contact, which would completely disarrange the signals and render the same unreliable; but by my construction the actuating-lever when released at once returns to its central position and stops, allowing the cylinder 16 to return at will by gravity to its normal position. The first action of the cylinder after being released on account of the vent-hole 18 is to drop quickly until said vent reaches the head or top surface of the piston 9, thereby quickly taking up all of the lost motion of the mechanism. The piston then continues downward slowly, the weight of the same gradually withdrawing the contact-lever 23 from its contact-fingers 24 until said contact-lever is about to break its connection therewith, at which time the vent-hole 18 reaches the opening 15 in the piston, which allows said cylinder to again drop quickly, and thereby instantly draw the contact-lever from its finger-contacts, making a quick break in the connection, which, as is well known, is of utmost importance in all mechanism where high-tension currents are employed. The length of time of this contact is nicely controlled by the distance between the head or upper face of the piston and the opening 15, and all of the lost or excess motion due to the unevenness of the throw in the actuating-lever or other mechanism is taken up instantly by the initial quick return of the mechanism above described. This uniformity in the contact period or quick return to a given point is an essential feature, as oftentimes a number of cars pass in close succession, and it is essential that this lost motion should be instantly taken up and only the necessary time given to the contact to enable the system to work properly and then be returned to its normal position in time to be again actuated by the next car, which may follow but a few seconds after. When a passing car travels in the opposite direction, the actuating-lever engages and operates the duplicate mechanism on the other side of the lever.

Having thus described my invention, what I claim as new, and desire to secure by Letters Patent, is—

1. In a circuit-closer, a pair of contacts, a pair of contact-arms, means including an actuating-lever whereby one of said arms may be positively actuated to close the circuit each time a car passes, and means including

a reciprocating cylinder arranged to limit and control the period of contact and also causing a quick break in the circuit.

2. In a circuit-closer, a pair of contacts, a pair of contact-arms, means including an actuating-lever whereby one of said arms may be positively actuated to close the circuit each time a car passes, and means including a reciprocating cylinder for quickly taking up the excess motion of the parts and then prolonging the period of contact, said cylinder being also adapted to cause a quick break in the connection.

3. In a circuit-closer, a pair of contacts, a pair of contact-arms, means including an actuating-lever whereby one of said arms may be positively actuated to close the circuit each time a car passes, a non-reciprocating piston, and means including a reciprocating cylinder working over said piston arranged to limit and control the period of contact and also causing a quick break in the connection.

4. In a circuit-closer, a pair of contacts, a pair of contact-levers, a two-way moving actuating-lever pivoted to the frame to close one or the other contacts of the pair according to which way it is moved, means including a reciprocating cylinder for prolonging the period of contact and also to cause a quick break in the connection, and means for engaging and positively stopping said actuating-lever when it returns to its central position.

5. In a circuit-closer, a pair of contacts, a pair of contact-levers, a two-way moving actuating-lever pivoted to the frame to close one or the other contacts of the pair according to which way it is moved, means for controlling the period of contact, means for engaging and positively stopping said actuating-lever when it returns to its central position, and means whereby said actuating-lever is released when said controlling means has returned to its normal position.

6. In a circuit-closer a pair of contacts, a pair of contact-levers, a two-way moving actuating-lever pivoted to the frame to close one or the other contacts of the pair according to which way it is moved, an endwise-moving cylinder adapted to control the period of contact, means for engaging and positively stopping said actuating-lever when it returns to its central position, and means whereby said actuating-lever is released when said cylinder has returned to its normal position.

7. In a circuit-closer, a pair of contacts, a pair of contact-levers, a two-way moving actuating-lever pivoted to the frame to close one or the other contacts of the pair according to which way it is moved, means including a reciprocating cylinder for prolonging the period of contact and also to cause a quick break in the connection, a locking member positioned by one movement of said

- actuating-lever to engage and positively stop said lever on its return stroke, and means whereby said actuating-lever is released when said cylinder has returned to its normal position.
8. In a circuit-closer, a pair of contacts, a pair of contact-levers, a two-way moving actuating-lever pivoted to the frame to close one or the other contacts of the pair according to which way it is moved, means including a cylinder for prolonging the period of contact and also to cause a quick break in the connection, and a locking member positioned by one movement of said actuating-lever to engage and positively stop said lever on its return stroke.
9. In a circuit-closer, a pair of contacts, a pair of contact-levers, a two-way moving actuating-lever pivoted to the frame to close one or the other contacts of the pair according to which way it is moved, means including a cylinder for prolonging the period of contact and also to cause a quick break in the connection, and a locking member positioned by one movement of said actuating-lever to engage and positively stop said lever on its return stroke.
10. In a circuit-closer, a pair of contacts, a pair of contact-levers, a two-way moving actuating-lever pivoted to the frame to close one or the other contacts of the pair according to which way it is moved, means including a cylinder for prolonging the period of contact and also to cause a quick break in the connection, and a locking member positioned by one movement of said actuating-lever to engage and positively stop said lever on its return stroke.
11. A circuit-closer comprising an actuating-lever, a pair of reciprocating cylinders arranged to limit and control the period of contact, means including said actuating-lever by which one of said cylinders is given an endwise movement when said lever is thrown in one direction, a pair of contacts, a pair of contact-arms independently hung, means whereby said cylinder-moving means will engage and positively move one of said arms into contact when one of said cylinders is raised.
12. A circuit-closer comprising an actuating-lever, a pair of reciprocating cylinders, separate means connected to each cylinder and extending into the path of the actuating-lever whereby said cylinder is moved, a pair of contacts, a pair of contact-arms independently hung, means whereby said cylinder-moving means will engage and positively move one of said arms into contact when one of said cylinders is raised, and a locking member positioned by one movement of said actuating-lever to engage and positively stop said lever when it returns to its central position.
13. In a circuit-closer, a pair of contacts, a pair of contact-arms, a two-way moving actuating-lever pivoted to the frame to close one or the other contacts of the pair according to which way it is moved, means including an endwise-movable cylinder for prolonging the period of contact, and a locking member positioned by one movement of said actuating-lever to engage and positively stop said lever on its return stroke.
14. In a circuit-closer, a pair of contacts, a pair of contact-arms pivotally hung in the frame, a two-way moving actuating-lever pivoted to the frame and arranged to positively close one or the other contacts of the pair according to which way it is moved, means including an endwise-movable cylinder for prolonging the period of contact and causing a quick break in the connection, and a locking member positioned by one movement of said actuating-lever to engage and positively stop said lever on its return stroke.
15. In a circuit-closer, a pair of contacts, a pair of contact-arms, means including an actuating-lever whereby one of said arms may be actuated to positively close the circuit each time a car passes, a non-reciprocating piston pivotally held, an endwise-moving cylinder working over said piston and arranged to prolong the period of contact.
16. In a circuit-closer, a pair of contacts, a pair of contact-arms, means including an actuating-lever whereby one of said arms may be actuated to positively close the circuit each time a car passes, a non-reciprocating piston, an endwise-moving cylinder working over said piston and arranged to prolong the period of contact, and means in said cylinder whereby the same will start back quickly to take up the excess motion of the parts and then move slowly to prolong the period of contact.
17. In a circuit-closer, a pair of contacts, a pair of contact-arms, means including an actuating-lever whereby one of said arms may be actuated to positively close the circuit each time a car passes, a non-reciprocating piston pivotally held, an endwise-movable cylinder, and means in said cylinder whereby the same will start to return quickly to take up the excess motion of the parts and then move slowly to prolong the period of contact and finally move at an accelerated speed and cause a quick break in the connection.
